(57) **CLAIM**

The ornamental design for a combination wrench as shown and described.

DESCRIPTION

FIG. 1 is a perspective view of a combination wrench showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a locally enlarged view of the combination wrench taken along circle 8 as shown in FIG. 6; and,

FIG. 9 is a locally enlarged view of the combination wrench taken along circle 9 as shown in FIG. 6.

The dash-dash broken lines shown in the drawings are included for the purpose of illustrating portions of the combination wrench that form no part of the claimed design. The dot-dash broken lines of FIGS. 6, 8, and 9 depict the limits of the enlarged views and form no part of the claimed design. The dot-dash lead lines in FIG. 6 labeled 8, and 9 indicate the areas from which the enlargements shown in FIGS. 8 and 9 are taken and form no part of the claimed design.
